No. 635,570.

Patented Oct. 24, 1899.

W. B. MILLER.
FARM GATE.

(Application filed Aug. 16, 1899.)

(No Model.)

UNITED STATES PATENT OFFICE.

WILSON B. MILLER, OF MCKENZIE, TENNESSEE.

FARM-GATE.

SPECIFICATION forming part of Letters Patent No. 635,570, dated October 24, 1899.

Application filed August 16, 1899. Serial No. 727,402. (No model.)

To all whom it may concern:

Be it known that I, WILSON B. MILLER, a citizen of the United States, residing at McKenzie, in the county of Carroll and State of Tennessee, have invented certain new and useful Improvements in Farm-Gates, of which the following is a specification.

The gate is mounted to swing upon a bottom pivot between two diagonally-placed posts, which hold the gate in position for suspension and for swinging upon the single pivot, and my improvement is directed to means whereby the gate is opened and closed, in connection with means whereby the gate is unlatched, both means acting together in a novel way, and in conjunction with a post-lever and the suspending-wire to both unlatch and open and close the gate, as I shall more particularly set out in the claims concluding this specification.

The accompanying drawings illustrate my improved gate, which, in—

Figure 1, is seen closed, the gate latch-bar being shown as unlatched by the post-lever, so that a further pull in the direction of the arrow 1 on the post-lever will by its connection with a suspending-wire cause the gate to swing open. Fig. 2 is a like view, the gate latch-bar being shown as engaged with the post-catches. Fig. 3 is a top view showing the post-lever and its gate and latch and gate connecting wires in their normal positions.

Fig. 4 is a side view of the same. Fig. 5 shows in detail the connection of the lever-suspending wire with the gate.

A single bottom pivot 2 (shown by dotted lines at the inner end of the gate) enters a sill-piece 3, placed between posts 4 4, which are put diagonally on each side of the sill and between which the gate is held in position to swing in being opened and closed. At its other end the gate has a double-ended latch-bar 5, pivoted meditately of its length and adapted to engage the catches 6 6, fixed at the bottom and at the top of the gate-post 7.

At the top above the gate the diagonal posts are connected by a cap which crosses diagonally over the pivoted end of the gate, and from this cap the gate is suspended, so that as it swings to open it has a slight lifting or tilting on its single pivot, which renders it self-

closing. I make this cap slotted or of two parts, from the under part 8 of which the gate is suspended by a double wire 9, which is passed under a pin near the front part of the gate at 10, below the middle of its height, and is looped at 11 in the latch-bar below its pivot 12. This suspending-wire 9 passes to the latch-bar from the post-cap 8 within a notch 13, Fig. 3, in the rear edge of which it is looped and passes down the opposite sides of the gate under the pin 10 in the gate-frame, so that the weight of the gate is utilized to keep the gate-latch engaged. This looped wire is strong enough to sustain the weight of the gate by its pull upon the latch-bar, and for this purpose the wire 9 rests in an intermediate suspending-yoke 14 at the top of the gate, which may be adjusted by the notches in the top bar or otherwise nearer to or farther from the pivoted end of the gate to sustain the gate in proper relation to its post-latches.

A feature of my improvement is a supplemental suspending-wire 15, which has no connection with the latch-bar, but which is looped to the gate-bars at or near the suspending-point 10 of the latch-connecting wire and is connected to the end of a lever 16, which is pivoted between the post-caps, so that the wire 15 passes therefrom on both sides of the gate to its point of suspension, at which it is preferably looped with the gate-bars, as seen in Fig. 5.

The post-lever 16, the handle 17 of which projects between and back of the post-caps, is connected to rods 18 18, which extend along the road at both sides of the gate and are supported in posts, so that the rods may be pulled or pushed by persons approaching the gate from either side to vibrate the cap-lever, which by pulling upon its connected wire 15 causes the gate to swing open or to be closed. I have not shown these rod-supporting posts, because they are well known as a means of supporting opening and closing rods; but the new feature in connection with these rods is the cap-lever and its connection with supplemental suspending-wire 15 and the latch-connecting wire 19.

It will be understood that the manner of suspending the gate causes its weight to be borne primarily by the suspending-wire 9,

which constantly pulls to keep the latch-bar engaged with the post-catches. To unlatch the bar by the post-lever, a wire 19 connects the post-lever with a lever 20, pivoted to the 5 upper part of the gate near its latch and standing upward above the top bar, and which is in turn connected to the upper end of the latch-bar by a short wire 21, so that the pulling or pushing of the handle of the post-lever 10 first unlatches the latch-bar and then instantly swings the gate open primarily by the supplemental suspending-wire 15 and con- jointly by the latch-connecting wire 19.

As stated, the gate will close itself when 15 opened by reason of the pulling action of the primary suspending-wire 9 from its connection with the cap; but it may be closed by pushing or pulling the handle of the post-lever.

The two suspending-wires reinforce each 20 other and form a durable means of supporting and controlling the gate.

When the gate is open, its weight keeps the latch-bar always in position to be engaged when closed with the post-catches.

25 The suspending-wire 9 can be set in the cap notches to bring its pulling force more or less obliquely to the line of the gate when closed, as in Fig. 3, while the post-lever can also be set farther from or toward either post, as may 30 be found necessary to control the swing and set of the gate.

A fixed bar 22 is placed beside the latch-connecting lever 21 to protect the latter from being pushed by stock which might open the 35 gate.

The gate may be unlatched by the hand-lever 20 and pushed open, and it will be understood that the opening movement of the gate brings into action the lifting effect of the sus- 40 pending-wire 9, and hence tilts the gate on its single pivot, and thereby renders it self-closing.

I claim as my invention—

1. The combination with the gate mounted on a single bottom pivot, the double latch-bar 45 and the suspending-wire connecting the latter with a fixed post-cap, of a supplemental suspending-wire connected to the swing end of the gate, a post-lever connected to the said supplemental wire at the pivoted end of the 50 gate, and rods for actuating said post-lever, to cause the gate to swing open when unlatched.

2. The combination with the gate pivoted to swing on its inner lower end, the double 55 latch-bar and the suspending-wire connected to the latter and a fixed post-cap, of a lever connected to the upper end of the latch-bar, a lever pivoted in the fixed post-cap, a wire connecting both levers, and rods connecting 60 the said cap-lever.

3. In combination with the gate mounted on a single bottom pivot, the double latch-bar, and a wire suspending the gate connecting the latch-bar with a fixed post-cap, of a lever 65 pivoted to the post-cap, a supplemental suspending-wire connecting the swing end of the gate with the post-lever, with a wire connecting the said post-lever and the upper end of the latch-bar.

4. In a gate mounted to tilt and to swing upon a single pivot and in combination with the gate and the posts at its pivoted end, a lever pivoted at the top of said posts, a suspending-wire connecting the posts and the 75 gate, a suspending-wire connecting the post-lever and the gate and means for actuating said post-lever for the purpose stated.

In testimony whereof I affix my signature in presence of two witnesses.

WILSON B. MILLER.
